Inventor

HERMAN PINTEL

By His Attorney

James O'Brien

UNITED STATES PATENT OFFICE

HERMAN PINTEL, OF ARLINGTON, NEW JERSEY

CLOTHES RACK

Application filed December 14, 1928. Serial No. 325,970.

This invention relates to new and useful improvements in clothes racks, and has for its provision to provide a device of this character that may be conveniently attached to a window frame in order that it may be swung into or out of the building, and is adapted for supporting washed garments so that they may be properly dried while hanging in the open outside of the building.

10 Generally speaking, my improved rack consists of a frame having clothes supporting means associated therewith, and being equipped with means to employ said frame to be secured to the outside of a window frame 15 in order that the rack may be swung into the building when the sash is raised to facilitate the attachment of the clothes thereto. After the attachment of the clothes, the frame may be readily swung to the outside of the building 20 to permit the drying of the clothes in the atmosphere. Furthermore, after the device has been swung outward, the sashes may be raised or lowered at will, without in any manner interfering with the device.

25 An essential object of this invention is to provide such a clothes rack that may be manufactured and marketed at low cost, and that is well adapted for use in the drying of garments and the like by residents of apartment 30 houses.

With the foregoing and other objects in view as the nature of the invention will be better understood from the following specification in conjunction with the accompanying drawing, and wherein like reference characters indicate corresponding parts throughout the several views:

Figure 1 is a fragmentary vertical section through a window frame with which my device is associated, the full line illustration of the rack disclosing the device swung outwardly of the building, and the dotted line illustration when swung inwardly of the building to enable the articles to be attached to or removed therefrom, and

Figure 2 is a fragmentary horizontal section through one side of the window frame looking downwardly upon the rack, which is shown partially in cross section.

50 Now having particular reference to the

drawing, there is disclosed an ordinary type of window frame A, within which are movable the usual sashes B. My rack consists of a pair of end bars 5—5 of any suitable material, and of any desired dimensions. Adjacent opposite ends of these bars 5—5, the same are formed with registering threaded openings 6, the threads of one bar extending in a reverse direction to those of the other bar. These end bars are detachably interconnected by side bars 7—7 reversely threaded at their opposite ends for threaded engagement within the openings of the end bars 5—5 and obviously, when the bars 7—7 are turned in one direction, the end bars 5—5 will be drawn inwardly, and vice versa. Threaded through openings in the bars 5—5 is a single length of cord or rope to produce spaced parallel horizontal runs 8, to which the clothes may be conveniently pinned as illustrated by the full and dotted lines in Figure 1. The rack further consists of an elongated supporting bar 9, threaded adjacent its outer end for threaded engagement within a central opening 10 of the outermost end bar 5. The opposite bar 5 is formed centrally with a wide unthreaded opening to enable the bar 9 to move freely therethrough. The end of the bar 9 beyond the threads 10 is of reduced diameter, so that it may be arranged through the said threaded opening 10 of the outermost bar 5 and provide a handle 11. The opposite end of this bar 9 is threaded and is adapted for engagement within a threaded socket 12 associated with one leaf of a relatively elongated hinge 13, the other leaf adapted for rigid association with one side of the window frame A, exteriorly of the building as disclosed.

Obviously, the bar 9 may be simultaneously threaded into the frame bar 5, and into said socket 12 by turning the handle end 11 of said bar. Furthermore, when it is desired to apply or remove the clothes, the sash is raised, and the rack then swung inwardly of the building as per the dotted lines in Figure 1. When the clothes are to be dried, the device is swung outside of the building as disclosed by the full lines in the same figure. The sash

may then be closed to prevent a draft in the room.

Furthermore, when the device is not being used, it may be quickly detached from the window and knocked down, after which it may be placed in suitable storage, and without requiring much space.

When in use any slack which may occur in the runs 8, due to stretching of the cord, as often occurs when new cord or rope is being used, may be taken up by rotating the bar 7 in a manner to spread the end pieces 5 apart. It is to be understood that the end pieces 5 do not have to be removed from the bar 9 when the device is taken down, as it is only necessary to release the end of the strand 8 and remove the bar 7, after which the innermost end piece 5 may slide toward the other end piece with the strands 8 threaded therethrough as will be apparent.

Having thus described my invention, what I claim as new and desire to secure by Letters Patent, is:

In a clothes rack of the class described, a frame consisting of a pair of end bars having unthreaded aligned base openings and further having adjacent their ends threaded openings, the threads of one bar extending in, reverse direction to those of the other bar, a pair of side bars reversely threaded at their opposite ends and adapted for simultaneous threaded engagement within the openings of said end bars, and means associated with said frame to facilitate the attachment of clothes thereto, comprising a flexible strand having its opposite ends anchored to the frame and its intermediate portion passed through the unthreaded opening and extending back and forth between the bars, said side bars constituting the means for tightening the strand, and an elongated supporting bar slidably extending through one of the end bars and threaded through the other end bar and terminating at one end in a reduced handle forming portion and having means at its opposite end for hingedly mounting same on a support.

HERMAN PINTEL.
